UNITED STATES PATENT OFFICE.

CHARLES G. BURKE, OF RICHMOND HILL, NEW YORK.

REGULATOR FOR ELECTRIC MOTORS.

SPECIFICATION forming part of Letters Patent No. 298,550, dated May 13, 1884.

Application filed November 22, 1883. (No model.)

To all whom it may concern:

Be it known that I, CHARLES G. BURKE, a citizen of the United States, residing at Richmond Hill, in the county of Queens and State 5 of New York, have invented certain new and useful Improvements in Apparatus for Regulating and Controlling Electric Motors, of which the following is a specification.

My invention relates to certain improvements in the method of and apparatus for regulating the speed of electric motors.

The object of the invention is to provide means whereby the rate of revolution of the armatures of electric motors of well-known 15 construction may be regulated without modifying the strength of the electric currents employed for actuating the same.

The invention consists in applying to an electric motor which is actuated by electric 20 impulses transmitted through each of a series of actuating electro-magnets in succession a device which may be so adjusted as to modify the duration of the successive impulses thus transmitted. By this means the periods during 25 which the successive electro-magnets exert an attractive force upon the armature are modified, and the consequent speed of the armature is regulated.

In the accompanying drawings, which illustrate 30 my invention, Figure 1 is a plan view of the motor, partly in section, and Fig. 2 is a vertical section of the same. Fig. 3 is a detached view showing certain details of construction. Fig. 4 illustrates a modification in 35 the construction of the second circuit-closer, and Fig. 5 is a diagram illustrating an organization of circuits as applied to the invention.

Referring to the drawings, A represents the base upon which the various parts of the motor 40 are supported, and B', B², and B³ represent three electro-magnets having their poles projecting toward a common central axis, c, of an armature, C. The poles of the electro-magnets terminate in a cylindrical case, b', of non-magnetic material. A rotating armature, C, 45 is supported within this case, and is constructed with four soft-iron extensions, c', c², c³, and c⁴. The armature C is mounted upon a vertical axis, c, which permits of the revolution of the 50 armature in response to the attraction exerted by the several electro-magnets in succession.

The electro-magnets are vitalized by means of an electric current which is transmitted to the electro-magnets in the proper succession by means of a circuit-controlling device, D, applied to the shaft c. The device D consists of four contact-points, d', d², d³, and d⁴, which are designed to be successively placed in electrical connection with three contact rollers or brushes, e', e², and e³. The contact-points d are 55 all in electrical connection with one pole of an electric battery through the shaft c of the armature and a binding-screw, 1. The contact brushes or rollers e', e², and e³ are respectively placed in electrical connection with the outer 60 terminals of the coils of the respective electro-magnets B', B², and B³, the inner terminals of which coils are in electrical connection with each other through a metallic ring, b, secured to but insulated from the base A of the instrument. The ring b is designed to be placed 65 in electrical connection with the remaining pole of the battery by means of a conductor attached to a binding-post, 2. The function of the circuit-controller D is the same as that 70 of the corresponding circuit-controller in any 75 of the well-known forms of electric motors, the revolution of the armature serving to place one of the contact-points in electrical connection with the contact-roller which is connected with the coils of the next succeeding 80 electro-magnet of the series, thereby causing the armature to be advanced until it has reached the neutral point of that electro-magnet, whereupon the circuit-connections are 85 completed by the action of the next succeeding circuit-closer through the coils of the next electro-magnet, and this succession of connections will be continued indefinitely by 90 the revolution of the armature. It is evident, 95 therefore, that the rapidity with which the armature will revolve when this circuit-controller alone is employed will be primarily dependent upon the inertia of the armature and the strength of the current of electricity, and that if these two elements are constant 100 the rate of revolution will also be practically constant. If, however, it is desired to modify this rate more or less, it would be necessary to modify the strength of the battery or the current received therefrom, or to adjust the position of the circuit-closing rollers with ref-

erence to their respective electro-magnets. The former method is, for obvious reasons, imperfect, and the latter method is undesirable, for the reason that it necessitates the adjustment 5 of the commutator-brushes to such positions that the effective force of the respective electro-magnets will be diminished by reason of the greater distance through which they are forced to act upon the armature, while the 10 amount of current through which they are vitalized is not changed. Such a method of adjustment would therefore necessitate a waste of electrical energy.

For the purpose of securing the required 15 adjustment without involving such loss of energy, I apply to the shaft *c* a second circuit-closing device, *H*. This device consists of four contact-points, *h*', *h*², *h*³, and *h*⁴, which are in 20 electrical connection, through the shaft *c*, with the four points *d*', *d*², *d*³, and *d*⁴, and are preferably though not necessarily located in the same vertical lines. A single contact-brush, *h*, is represented in Fig. 3 for completing the 25 connections of a battery through these points in succession during the revolution of the armature. The contact-brush *h* is placed in electrical connection with a binding-post, 3, and it is rendered adjustable in a manner hereinafter described. It will be seen, thus, 30 that if one pole of the battery be connected with the ring *b*, and the remaining pole of that battery with the contact-brush *h*, the period during which the circuit of the battery will be completed through the corresponding contact- 35 roller will depend upon the position of the contact-brush *h* with reference to one of the contact-rollers *e*. Thus if the contact-brush *h* be in the same vertical line with one of the contact-rollers, *e*', it will remain in contact 40 with one of the contact-points *h*', *h*², *h*³, or *h*⁴ during the time one of the contact-points *d*', *d*², *d*³, or *d*⁴ is passing the contact-roller *e*', provided the extent of contact-surface of the two 45 systems of contacts is equal. If, however, the contact-brush *h* be so adjusted as to extend in a vertical line slightly differing from that of the circuit-closing point, the time during which the circuit of the battery will be completed through both that point and the 50 contact-brush *e*' will be correspondingly shortened, and the duration of the periods in which the attraction is exerted by the corresponding electro-magnet upon the armature will be correspondingly shortened. The rate of the revolution 55 of the armature will thereby be reduced.

I prefer to construct the contact-points *d* of sufficient width to insure the completion of the circuit-connections at all times through 60 some one of the contact-rollers *e*, thus avoiding any dead-points in the revolution of the armature.

For the purpose of readily adjusting the position of the brush *h*, I mount it upon a revolving carriage, *K*, which is provided with 65 a milled head, *k*', by means of which it may

be turned upon an axis concentric with the armature-axis *c*. The adjustment may, however, be rendered more accurate by means of a worm, *r*, and screw-thread *s*, acting upon 70 the head *k*' in the manner illustrated in Fig. 4. A graduated scale, *t*, Fig. 4, is also preferably applied to the motor, and an index, *m*, attached to the moving carriage *K*, projects over this scale, by means of which the position of 75 the contact-brush may be accurately determined.

It will be observed that, according to the construction illustrated in Figs. 2 and 3, the modified currents can be transmitted through 80 only the particular electro-magnet with which the contact-roller *e*' is connected. By supplying an independent contact-brush *h*, as shown at *h*', *h*², and *h*³ in Fig. 4, for each contact-roller *e*', *e*², and *e*³, respectively, each 85 electro-magnet may be employed for actuating the armature in precisely the same manner as described with reference to the contact-brush *h*. This latter organization is preferable for most purposes. There are two 90 methods whereby the adjustment may be employed—first, by supplying the entire current which is employed for actuating the motor through the brushes *h*, and, second, by applying a battery of sufficient force for over- 95 coming the inertia of the armature directly to the contact-rollers *e* through the binding-posts 1 and 2 and supplying the controlling-current through the brushes *h*. The adjustment of the 100 brushes *h* will in either case effect the required regulation of the movements of the armature. The latter method, which is of especial importance in cases where it is desired to employ a series of electric motors in a single electric circuit, and to cause each to rotate at the same 105 speed, is illustrated in Fig. 5. In this figure *M*', *M*², and *M*³ represent a series of three motors, each primarily actuated by electric currents from local batteries *o*', *o*², and *o*³, respectively connected with the binding-posts 1 and 110 2 of each motor. The controlling-currents are supplied from a battery, *O*, one of the poles of which is connected through the contact-brush *h* of the first or controlling motor with the succeeding motor, and through the earth with the 115 remaining pole of the battery. The strength of the current supplied by the battery *O* bears such relations to the currents from the batteries *o*', *o*², and *o*³ that it controls the speed of the several motors, which will all be actuated 120 at the same rate of speed.

It is evident that in this manner the circuit-controlling device *H*, applied to a single motor, may be employed for controlling the speed of the entire series, and this controlling-motor 125 may be any one of the series. The contacts of the brushes *h* of the other motors of the series are preferably continuous.

I claim as my invention—

1. The combination, substantially as hereinbefore set forth, of a revolving armature, a series of electro-magnets, a circuit-controlling

device for transmitting electric currents to said electro-magnets in the proper succession to actuate said armature, and a second circuit-controlling device for modifying the duration 5 of the electric currents thus transmitted.

2. The combination, substantially as hereinbefore set forth, with an electric motor, of an independent circuit-controlling device, whereby the duration of the electric currents 10 transmitted through the coils of said motor may be modified.

3. The combination, substantially as hereinbefore set forth, with a series of electro-magnets, an armature common to all of said magnets, a battery, and means, substantially such 15 as described, for transmitting electric impulses from said battery through said electro-magnets in succession, of a second battery and an adjustable circuit-controlling device, where-

by electric currents may be transmitted from 20 the last-named battery through said electro-magnets coincident with the first currents, but of less duration.

4. The hereinbefore-described method of regulating the speed of electric motors, which 25 consists in vitalizing the actuating electro-magnets through the agency of electric currents of determinate duration, and simultaneously supplying controlling-currents of less duration.

In testimony whereof I have hereunto subscribed my name this 1st day of November, 30 A. D. 1883.

CHARLES G. BURKE.
